GARMENT FASTENING DEVICE

Original Filed April 4, 1930

UNITED STATES PATENT OFFICE

BENJAMIN LIEBOWITZ, OF NEW YORK, N. Y., ASSIGNEE TO S. LIEBOVITZ & SONS, INC.,
OF NEW YORK, N. Y., A CORPORATION OF NEW YORK

GARMENT FASTENING DEVICE

Original application filed April 4, 1930, Serial No. 441,441. Divided and this application filed December 24, 1931. Serial No. 582,984.

This invention relates to fastening devices, more especially those adapted to be used in the folding of garments, as for instance, shirts, and is a division of an application filed by me on April 4, 1930, Serial No. 441,441.

In folding shirts at the laundry or factory, the present day practice is to use a series of pins throughout the garment each 10 of which pins is independently and successively applied in a series of separate operations. This securing of independent pins is not only time and labor consuming, but in addition the purchaser of the shirt is compelled laboriously to remove the pins, which latter are apt to prick and injure both the person applying as well as the purchaser removing the pins.

One object of the invention is to provide 20 a unitary fastening device which may be easily and quickly applied for holding the parts of a garment in folded position, and likewise easily and quickly removed without the foregoing objections attendant upon the use of 25 a multiplicity of separate pins.

Another object of the invention is to provide means for fastening a folded garment wherein the pin or fastening means are kept 30 covered.

A still further object of the invention is to provide a fastening device for securing 35 portions of a garment, such as a shirt or the like, in predetermined folded positions, which device is removable as a unit to unfasten the folded portions.

For a clear description of my invention, I refer to the drawing wherein several examples of carrying my invention into practice are shown.

Figure 1 shows my securing means as applied to a shirt;

Fig. 2 shows the two portions constituting my securing means;

Fig. 3 shows my invention when in its 45 securing position;

Fig. 4 shows the manner in which the cover operates to move the securing means to releasing position; and

Fig. 5 is a view similar to Fig. 3 of a modi-

fied form of the invention, wherein the cover is dispensed with.

Referring now more particularly to the drawing, Fig. 1 shows a shirt 10 to which my securing means 11 is applied for holding portions of the shirt in a certain folded position. Referring more particularly to Fig. 2, my securing means consist of a lower portion or base 12 which may be composed of paper, cloth, or other material, said portion 55 12 carrying a pair of spaced staples 13, or pin-like elements, which may be secured thereto in any manner. While I have shown a pair of staples 13, each consisting of two wire prong members, it is obvious that but 60 one staple 13 may be used, and that it may consist of a single wire prong or other fastening device.

In actual practice the portion 12 of the staple 13, may be inserted under part of the 70 shirt 10 or material 14 to be secured as is shown in Fig. 3. After the staples 13 are passed through the material the cover 15 may be placed over the same, the staples 13 being adapted to pass through perforations 16 of 75 the cover, which perforations, however, are not necessarily preformed as they may be formed by the passage of the staples themselves. The staples 13 are then bent over into the position of Fig. 3, that is with the two 80 prongs of each staple preferably bent in the same direction but oppositely and away from the bent prongs of the other staple, in which position they are disposed in securing or fastening position. Portion 17 of the cover 85 15 is then bent over to the position of Fig. 3 wherein it covers or envelopes and thus protects the staple 13. In this position, the portion 17 of the cover 15 is kept in covering relation to the staples by cooperation of the 90 slotted portions 18 at the ends of the cover, with the complementary slotted portions 19 formed in the body of the cover.

When it is desired to unfasten the shirt 95 for use, it is merely necessary to move the cover portions 17 in the direction of the arrow 20 from their position of Fig. 3 to the position of Fig. 4. It will be observed that this movement of the cover moves the staples 13 to an upright position so that the cover can 100

be removed, and the garment released from the staples with great ease and facility.

It is also possible to remove the base 12 and staples 13 as a unit without the necessity 5 of first straightening the staples or manipulating the cover. This may be done by inserting the fingers under the folded and fastened portions of the shirt or garment, and then pulling the base 12 out, thus withdrawing 10 or sliding the bent staples from engagement with the material of the garment and releasing the folded portions thereof.

In some instances the cover 15 may be dispensed with, and without exposing the bent 15 over portions of the staples 13. This may be effected by applying the base 12 to the outside instead of the inside of the folded portions of the garment and causing the staples to penetrate the material inwardly, and then 20 bending over the ends of the staples on the inside of the folded portions. This modified form of the invention is illustrated in Fig. 5, wherein the base 12 is shown applied to the outside face 14' of the material as distinguished 25 from the other form of the invention wherein the base 12 is engaged with or applied to the inside of the folded portions of the garment, and in this form of the invention it will be observed that the base 12 acts 30 as a protecting cover for the prongs which latter are disposed interiorly of the garment.

While I have shown but several embodiments of my invention, it should be understood 35 that modifications of the same within the scope of the appended claims will readily occur to one skilled in the art, the present illustrations of several ways by which the invention may be practiced being merely by 40 way of example.

What I claim is:

1. In combination with a shirt or like garment having sleeves which have portions folded upon the back of the shirt and having 45 a skirt folded upon said portions of the sleeves, unitary fastening means for the said folded portions having parts which penetrate each of the sleeve portions and also penetrate the skirt for securing all of said portions in 50 their folded position.

2. In combination with a shirt or like garment having sleeves which have portions folded upon the back of the shirt and having a skirt folded upon said portions of the 55 sleeves, the sleeves having cuffs which latter project upwardly beyond the skirt so as to be exposed for inspection, unitary fastening means for the said folded portions having parts which penetrate each of the sleeve portions and also penetrate the skirt for securing all of said portions in their folded position.

3. In combination with a shirt or like garment having sleeves which have portions 65 folded upon the back of the shirt and having

a skirt folded upon said portions of the sleeves, the sleeves having cuffs which latter are exposed for inspection, unitary fastening means for the said folded portions having parts which penetrate each of the sleeve portions and also penetrate the skirt for securing all of said portions in their folded position. 70

4. In combination with a shirt or like garment having sleeves which have portions folded upon the back of the shirt and having a skirt folded upon said portions of the sleeves, unitary fastening means for the said folded portions having parts which penetrate each of the sleeve portions and also penetrate the skirt for securing all of said portions in their folded position. 75

5. In combination with a shirt or like garment having shoulder portions folded upon the back of the shirt and having a skirt folded upon said shoulder portions, unitary fastening means for said folded portions having parts which penetrate each of the shoulder portions and also penetrate the skirt for securing all of said portions in their folded positions. 80

6. In combination with a shirt or like garment having sleeves which have portions folded upon the back of the shirt and having a skirt folded upon the said portions of the sleeves, unitary fastening means disposed upon the skirt for fastening said skirt to the sleeve portions to secure all of said portions in their folded position, said fastening means being removable as a unit by a single movement to release all of said folded portions simultaneously. 95

Signed at New York city, in the county of New York and State of New York A. D. 1931.
